UNITED STATES PATENT OFFICE.

LOUIS DORSAM, OF MILLVILLE, NEW JERSEY.

DESIGN FOR A FRAME FOR PICTURES, &c.

SPECIFICATION forming part of Design No. 25,038, dated January 7, 1896.

Application filed December 4, 1895. Serial No. 571,060. Term of patent 7 years.

To all whom it may concern:

Be it known that I, LOUIS DORSAM, a citizen of the United States, residing at Millville, in the county of Cumberland and State of New Jersey, have invented a new and original Design for Frames for Pictures and the Like, of which the following is a specification, reference being had to the accompanying drawing, illustrating the same.

10 The said drawing is a front elevation of a frame embodying my new and original design.

The essential characteristic feature of the design is the ornamental frame which surrounds the panel A or space in which may be placed a picture, mirror, or similar object which it is intended the frame should surround.

15 The lower portion of the frame has two short legs B B, as the frame is intended to rest upon a surface in an inclined position, as an easel.

The rim or outer edge of the frame is serrated, as indicated at C.

20 The opposite sides of the frame are straight and parallel with each other, while the top is curved or arched.

25 Surrounding the panel A, and just inside of

the serrated edge C, there are formed openings through the frame D, which are separated by bars E, such bars connecting the rim of the frame immediately surrounding the panel and 30 the serrated edge portion. The rim of the frame adjacent to the panel at the top is broader than is the rim at the sides, and is ornamented with a conventional ornament, such as the stars G.

35

Adjacent to the legs B are the pyramidal projections H, one at each corner of the frame, and between adjacent openings D.

A frame embodying my design may be made of glass, metal, wood, or other suitable material.

Having thus described my design and its essential characteristics, what I claim, and desire to secure by Letters Patent, is—

20 The design for a frame for pictures, and the like, substantially as shown and described.

In testimony whereof I have signed this specification in the presence of two witnesses.

LOUIS DORSAM.
